2 SHEETS—SHEET 2.

UNITED STATES PATENT OFFICE.

FRANK J. QUIST, OF WORCESTER, MASSACHUSETTS.

PNEUMATIC CARPET-SWEEPER.

1,190,798.

Specification of Letters Patent. Patented July 11, 1916.

Application filed June 26, 1912. Serial No. 705,898.

To all whom it may concern:

Be it known that I, FRANK J. QUIST, a citizen of the United States, residing at Worcester, in the county of Worcester and State of Massachusetts, have invented a new and useful Pneumatic Carpet-Sweeper, of which the following is a specification.

The principal objects of this invention are to provide an efficient combination between a pneumatic carpet sweeper of the well-known type in which the device is operated by rolling it along the floor, and a rotary brush, and particularly to provide a combination for this purpose in which the nozzle for receiving the air and directing it to the pneumatic suction device can be removed from the casing in a simple and expeditious manner without interfering with the connections by which the brush is driven except to temporarily disconnect them from the brush and to cause this temporary disconnection to be accomplished simply by the removal of the nozzle and the operative engagement to be restored by the mere replacement of the nozzle in operative position on the casing.

The invention involves an improved driving device for the brush; improved means for supporting the same; an improved nozzle in which the brush is located; an improved nozzle plate for contacting with the surface to be cleaned having means whereby the cleaning action can be applied to surfaces beyond the exterior outlines of the casing and close to the walls of the room; and improvements in the arrangement of the rotary brush itself relatively to the rest of the device.

Further objects and advantages of the invention will appear hereinafter.

Reference is to be had to the accompanying drawings in which—

Figure 1 is a side elevation of a pneumatic carpet sweeper constructed in accordance with this invention. Fig. 2 is a longitudinal central sectional view of a portion thereof in a plane parallel with the plane of Fig. 1. Fig. 3 is a bottom plan view of a portion of the device. Fig. 4 is a vertical sectional view taken through the center of the brush showing one end of the nozzle.

The invention is shown as comprised in a form in which a casing 10 is employed having a bottom 11 and a slanting partition 12 above the bottom. The bottom and this partition, with the side and end walls furnish

a receptacle for receiving the dust separator, as is well understood in this art. At the rear of this partition is a crank shaft 14 on which are wheels 15 provided with corrugated rubber surfaces designed to support this end of the casing and to bear on the surface being cleaned so that as the casing is moved over said surface, the wheels will rotate and cause the crank shaft to turn so as to operate the movable leaves 17 of the pneumatic suction creating devices which are located on top of the partition 12 within the casing. The details of this suction device or pneumatic motor will not be specified particularly, as any desired kind can be employed. They are connected by any suitable ports and valves through the partition 12 with the receptacle underneath which is designed as usual for the reception of the dust collector shown in this instance in the form of a bag 20. This bag is connected at its open front end with a frame 21 provided with leather or other packing on both sides thereof and just covering the opening in the bag receptacle. The side walls are provided with a pair of forwardly extending pins 22 which are received in slots 23 in the ends of this frame. They project beyond the frame and into sockets 24 in the inner edges of a nozzle 25. This nozzle is provided with a passage 26 in its rear wall communicating with the open mouth of the dust bag and the nozzle is hollow so as to receive a brush 27 therein.

This brush is shown as mounted on a shaft 28 formed of two or more pieces of wire twisted together and into which the bristles are bound. At the ends this shaft is provided with a pair of plates 28^a soldered or otherwise secured thereto, being preferably of metal and on these are supported a plurality of thin radial longitudinal vanes 29. The bristles obviously extend between these vanes and beyond them.

The shaft 28 is so located that the brush projects through the lower nozzle plate 30 which constitutes the operative face of the nozzle. This nozzle plate is provided with a wide opening 31 extending from end to end of the brush and constitutes the opening through which the air is admitted into the interior of the device. The nozzle plate is flat on the bottom so far as the surface is concerned which immediately surrounds this opening but its forward and rear edges are curved upwardly.

In order that the device may be used to

cover an area wider than that of the casing itself and beyond all the projecting parts thereon and extending very close to the walls of the room in which it is used, the nozzle 5 is provided with a pair of slots 32 at its ends extending outwardly from the opening nearly to the ends of the plate 30 and the plate is extended beyond the side walls of the casing as shown in Fig. 4. The 10 slots preferably gradually increase in height from their outer edges toward the main opening. The nozzle preferably is held in position by means of a hook 33 mounted on an eccentric 34 which has a handle 35. The 15 hook is adapted to come into engagement with a projection 36 secured to the end of the nozzle. One of these is employed on each end.

In order that the brush may be operated 20 effectively on different types of carpets and floors an adjusting device preferably is employed for this end of the casing. This is shown in the present instance in the form of a plate 37 set into the bottom of the 25 casing and a plate 38 pivotally connected therewith at one end and supporting a roller 39. An adjusting screw 40 is employed to vary the distance of the roller from the bottom of the casing.

30 The brush is driven by a sprocket wheel 45 mounted on the crank shaft 14 and provided with a flexible driving chain 46. This driving chain passes over an idler 47 on the casing and an end idler 48 located beyond 35 the end of the casing and beyond the shaft 28. This idler is mounted on an arm 49 pivoted at 50 on the casing and provided with an adjusting device 51 by which it can be swung up and down about the pivot. The 40 brush shaft 28 is provided with a sprocket wheel 52 on the end adapted to mesh with the chain. It is to be observed that this sprocket wheel is located below the lower strand of 45 the chain so that when the nozzle is applied to the casing the sprocket wheel comes up from below and engages the chain. At the same time it tightens the chain by moving it upwardly adjacent to the idler 48 so that a movement of the casing over the floor will 50 cause the rotation of the wheels to be transmitted directly and positively to the brush. Yet when it is desired to remove the nozzle and brush this can be done without disconnecting any of these parts because the 55 nozzle is simply lowered on the casing to bring the sprocket 52 out of engagement with the chain. This loosens the chain but does not affect the connections, the arm 49 being provided with a projection 54 to prevent the chain from being dislodged from the idler 48. It will be seen, therefore, that by this connection the positive operating 60 means for the brush is intact and is not disturbed when the brush and nozzle are removed.

Although I have illustrated and described a preferred embodiment of the invention and shown it as applied to one specific type of cleaning device, I am aware of the fact that many modifications can be made therein 70 by any person skilled in the art without departing from the scope of the invention as expressed in the claims. Therefore I do not wish to be limited to the details of construction herein shown and described or to the 75 particular type of machine illustrated, but

What I do claim is: —

1. In a pneumatic carpet sweeper, the combination with a casing, of a pneumatic suction device carried thereby, wheels for 80 supporting the casing and operatively connected with said suction device for operating it, a nozzle removably mounted on the casing and connected with said suction device, a brush mounted in said nozzle, means 85 supported by the casing for driving the brush, and means for automatically connecting the brush with said brush operating means when the nozzle is applied to the casing.

2. In a pneumatic carpet sweeper, the combination with a casing, of a pneumatic suction device carried thereby, wheels for 90 operating the suction device, a nozzle removably mounted on the casing and connected with said suction device, a brush carried by said nozzle, a flexible driving member 95 connected with said wheels and supported by the casing, and means carried by said nozzle for operatively connecting said brush 100 with the driving member when the nozzle is in position on the casing.

3. In a pneumatic carpet sweeper, the combination with a casing, of a pneumatic suction device carried thereby, wheels for 105 supporting the casing and operatively connected with said suction device for operating it, a nozzle removably mounted on the casing and connected with said suction device, a brush carried by said nozzle, a chain 110 supported by the casing for driving the brush, and a sprocket wheel fixed to the brush for connecting the brush with said chain when the nozzle is applied to the casing.

4. In a pneumatic sweeper, the combination with a casing, of supporting wheels carried thereby, an endless chain supported by the casing and connected with the wheels, a nozzle removably mounted on the casing, 120 a brush carried by said nozzle and having a sprocket wheel normally engaging the outer side of the lower strand of said endless chain, whereby when the nozzle is removed from the casing the sprocket wheel will 125 move out of engagement with the chain and will move into engagement therewith so as to be positively operated thereby when the nozzle is replaced on the casing.

5. In a pneumatic carpet sweeper, the 130

combination of a casing, supporting wheels therefor, a sprocket wheel connected with the supporting wheels, a nozzle removably mounted on the casing, an arm projecting 5 out from the casing over the end of said nozzle and having an idler thereon, an endless chain connecting said idler and sprocket wheel, a brush carried by the nozzle, and a sprocket wheel on the brush meshing with 10 the outer side of the lower strand of said chain.

6. In a pneumatic carpet sweeper, the combination of a casing, supporting wheels therefor, a sprocket wheel connected with 15 the supporting wheels, a nozzle on the casing, an arm pivoted on the casing and projecting out from the casing over the end of said nozzle and having an idler thereon, a brush carried by the nozzle, a sprocket wheel 20 on the brush, a chain on said sprocket wheels, and means for adjusting the arm about its pivot to control the tension of the chain.

7. In a pneumatic carpet sweeper, the 25 combination with a casing, of wheels for supporting the casing, a nozzle removably mounted on the casing and provided with a wide opening in the bottom surface thereof, a brush located in said nozzle in position to 30 project through said opening in the nozzle, means supported by the casing for driving the brush from the wheels, and means on the nozzle for connecting the brush with said brush operating means when the nozzle is 35 applied to the casing.

8. In a carpet sweeper, the combination of a casing, driving and supporting wheels thereon, an endless chain connected with and driven by said wheels, a rotary brush on the casing having a sprocket wheel thereon meshing with the lower side of the lower strand of said chain, and bearings for said brush removable from the casing downwardly away from said lower strand. 40

9. A carpet sweeper comprising a nozzle 45 having an opening in the operative face thereof, a brush mounted to rotate in said opening and comprising a plurality of longitudinal radial vanes, bristles between said vanes projecting through the opening in the 50 nozzle, and means for drawing the dust away from said brush.

10. A carpet sweeper comprising a hollow nozzle having a wide inlet opening extending from end to end, a brush mounted to 55 rotate in the nozzle and projecting through said opening, said nozzle having an operative face extending beyond the ends of said opening and provided with two opposite aligned free slots at its ends narrower than 60 said inlet opening and extending outwardly from the ends of the opening and of the brush for taking up the dust.

In testimony whereof I have hereunto set my hand, in the presence of two subscribing 65 witnesses.

FRANK J. QUIST.
